UNITED STATES PATENT OFFICE.

DOMENICO M. DAVINO, OF NEW YORK, N. Y.

WINDOW CONSTRUCTION.

1,290,719.

Specification of Letters Patent.

Patented Jan. 7, 1919.

Application filed May 11, 1917. Serial No. 167,886.

To all whom it may concern:

Be it known that I, DOMENICO M. DAVINO, a subject of the King of Italy, and resident of New York, in the county and State of New York, have invented certain new and useful Improvements in Window Construction, of which the following is a specification.

This invention relates to window construction, and it has particular relation to that class of such constructions whereby the suspension cords of the sashes can be readily and conveniently renewed without dismembering any part of the window frame and without removal of the sash from its normal operative position within the frame.

It is the object of my invention to provide a simple and improved window construction of the class described which will, in its adaptability for access to the sash suspension cords, possess advantages in point of simplicity and inexpensiveness in construction, surface appearance, convenience, effectiveness, ease of operation, and general efficiency.

In the drawings—

Figure 1 is a face view, partly in section, of a window construction having my improvements.

Fig. 2 is a detail horizontal cross-section, on the line $\alpha-\alpha$, Fig. 1.

Fig. 3 is a detail perspective view of the face closure for the sash at the cord recess.

Corresponding parts in all the figures are denoted by the same reference characters.

Referring to the drawings, 1 designates the window frame, which may be in the main of any usual or adapted construction comprising the vertical side pockets, 2—2, within which the weights operate in their vertical line of travel, and having at the face of the inner wall, 3, of the side pocketed portions the projecting vertical strips, 4, between which the sashes are retained and guided in their vertical line of travel, the inner wall 3 being also provided near the top with the usual slot, 5, for the passage of the suspension cord in its mounting over the pulley, 6, which is carried internally of said wall and constitutes the suspension means for the cord and gravity weight.

The textile suspension cords, 7, and the gravity weights, 8, are of any usual construction, and in the usual operative relation as a counterbalance for the respective sashes. The window sashes, 9, are in the

main of any usual or adapted construction slidably operative within the window frame between guide strips 4, and the side stiles of the sashes are provided with the usual groove, 10, in their outer edges, for the accommodation of the suspension cord and terminating at the point at which the terminal end of the cord is connected to the sash.

In connection with the conditions of window construction in which my invention and improvements are designed to be employed, access is afforded to the weight pockets 2, and for this purpose the inner wall 3 of the window frame may be provided with a section at the lower end of the weight pockets, as at 11 (Fig. 1), which can be opened to expose the weights and the terminal ends of the suspension cords which are connected therewith.

My improvements have particular relation to the means for affording convenient access to the terminal ends of the suspension cords, to enable the securing thereof to and their detachment from the sash, while the sash is in normal operative position and without removing the same from the window frame. To these ends, my improved construction for this purpose comprises a recess, as at 18, provided at a suitable point internally of the side stile of the sash and opening outwardly at the face of the latter, as at 19. Said recess also has a channel, as at 20, extending upwardly internally of the stile of the sash and intersecting the bottom of the sash edge-groove 10 in which the suspension cord extends.

The closure provided for the face opening 19 of the recess 18, to avoid any impairment of the appearance or surface conditions at the face of the sash stile, comprises in my improved construction a plate, 21, secured in countersunk position at the surface of the stile and extending on the surface plane thereof, and having an opening, 22, registering with the internal recess 18 and affording access thereto. Said face plate 21 may be finished uniformly with the sash surface so that it does not impair the facial appearance thereof. Means are further provided for closing the access opening 22 of the plate 21, so that the sash stile will present substantially a normal appearance notwithstanding the construction whereby access is afforded to the suspension cords, and the improved construction for this purpose

comprises a plate, 23, which is pivotally mounted, as at 24, in a corresponding recess formed in the sash stile beneath the face plate 21 and opening at the inner edge of the stile, said pivoted plate preferably also having an extension or wing, 25, projecting at right angles to its main portion and accommodated in a corresponding recess at the inner edge of the sash stile, which extension is adapted to be engaged by the finger of the operator to swing the pivoted plate 23 from its normal position and thus expose the internal recess 18 which forms a socket for the terminal end of the suspension cord. The pivoted plate 23 is fulcrumed at its bottom, as herein shown, and the axis of the fulcrum is such that the plate will retain its normal position as a closure for the opening 19 in the face plate 21, in which position the pivoted plate is concealed beneath the face plate and the general appearance of the face of the sash stile is substantially the same as if the sash embodied no construction for affording access to the suspension cord.

In a window provided with my improved construction, to renew the suspension cords, by removal of the old cords and the substitution of new cords, it is simply necessary to open the section 11 at the bottom of the weight pockets to afford access to the weights and the cord connections therewith, and to swing the pivoted closure plate 23 from its recess to afford access to the internal recess or socket for the knotted ends of the cords whereby they are retained in connection with the sash. The old cords can then be readily disconnected at their connection ends from both the weight and the sash and drawn out at either of the open terminals. Then, to insert and connect the new suspension cords, it is simply necessary to pass one end of the cord through the slot opening 5 in the window frame and over the pulley 6 and feed it down until its end reaches the weight 8, to which it is then connected, and the other end of the cord is then fed downwardly in the sash edge groove 10 to the internal recess or socket 18 and through the front opening thereof, when it may be knotted in the usual manner and returned to said recess to form an anchored connection with the sash, after which the

pivoted closure plate 23 and the section 11 are returned to normal position. It will be noted that, in the improved construction as comprised in my invention, the supplementary closure plate 23 operates in a corresponding recess in the sash stile immediately beneath the face plate 21 which is countersunk at the face of the stile and flush with the surface thereof and permanently secured thereto, and that said supplementary closure plate is pivoted to swing laterally at the inner edge of the stile to open or close the opening in the overlying face plate, whereby none of said elements affording access to the stile socket are projective at the face of the stile either in their secured normal or operative positions. It will be further noted that said laterally-swinging under closure plate has the axis of its fulcrum so disposed that the closure plate will automatically retain its normal position within its recess in the stile and be concealed beneath the face plate.

Having thus described my invention, I claim and desire to secure by Letters Patent:

An improved window construction of the class described, comprising the sash stile having an internal recess forming an anchorage socket for the end of the suspension cord, a face plate countersunk at the face of the stile and flush with the surface thereof and permanently secured thereto and having an opening registering with said internal socket, and a supplementary closure plate operating in a corresponding recess in the sash stile immediately beneath said face plate and pivoted to swing laterally at the inner edge of the stile to open or close the opening in the overlying face plate, whereby none of said elements affording access to the stile socket are projective at the face of the stile either in their secured normal or operative positions, said laterally-swinging under closure plate having the axis of its fulcrum so disposed that the closure plate will automatically retain its normal position within its recess in the stile and be concealed beneath the face plate, substantially as and for the purpose set forth.

In testimony whereof I have signed the foregoing specification.

DOMENICO M. DAVINO.
